Primary Examiner — Elizabeth Albert(74) *Attorney, Agent, or Firm* — Robert H. Jordan(57) **CLAIM**

The ornamental design for a sheet dispenser and writing instrument holder, as shown and described.

DESCRIPTION

FIG. 1 is a left front perspective view showing the new design for a sheet dispenser and writing instrument holder;

FIG. 2 is a front elevation view thereof;

FIG. 3 is a back elevation view thereof;

FIG. 4 is a top plan view thereof;

FIG. 5 is a bottom plan view thereof;

FIG. 6 is a right side elevation view thereof; and,

FIG. 7 is a left side elevation view thereof.

The broken lines showing the note paper outlet in FIGS. 1, 2, 4, 6, and 7 are included for the purpose of illustrating a portion of the holder that forms no part of the claimed design.
